UNITED STATES PATENT OFFICE

2,525,002

DOOR LOCKING MEANS

Harvey J. Smith, Greensboro, N. C.

Application December 22, 1947, Serial No. 793,116

4 Claims. (Cl. 312—193)

1

My invention relates to racks of the kind disclosed in and covered by my U. S. Letters Patent No. 2,320,159, issued May 25, 1943, No. 2,343,248, issued March 7, 1944, and No. 2,432,455, issued December 9, 1947 and that disclosed in my patent No. 2,443,837, issued June 22, 1949.

The present invention has for its object to provide an improved cover construction for the can stacks and a simplified locking mechanism for the same and for the door which closes the can and tool entrances on the front wall.

To the attainment of the aforesaid objects and ends invention still further resides in the novel details of construction, combination and arrangement of parts, all of which will be first fully described in the following detailed description, and then be particularly pointed out in the appended claims, reference being had to the accompanying drawing, in which:

Fig. 1 is a side elevational view of my improved rack, looking from left to right in Fig. 2.

Fig. 2 is a front elevation of the same.

Fig. 3 is a detail horizontal section on an enlarged scale, taken on the line 3—3 of Fig. 2.

Fig. 4 is a detail elevation of the cam disc, a portion of one of the locking levers being indicated in dot and dash lines to show its relation to the cam disc in the locked position.

Fig. 5 is an enlarged detail vertical section on the line 5—5 of Fig. 2.

Fig. 6 is an enlarged detail horizontal section on the line 6—6 of Fig. 2.

In the drawings in which like numerals and letter of reference indicate like parts in all the figures, 1 is the base, 2 the front wall, 3 the back wall, 4 the can separator side walls, and 37 the top of the rack.

The front wall 2 has inwardly bent portions 2^a and stepped portions 2^b the sides of which are bent back as at 2^c to clamp over the sides 4^a of the side walls 4. Each wall 4 is preferably formed of a single piece of sheet metal, the sides 4^a of which project outwardly at right angles to the wall proper. The metal is further bent over and back on itself at intervals to form the intermediate partition 4^b, between which projections 4^a, 4^b cans may be stacked. The back wall plate 3 is bent similarly to the front wall plate 2 to provide corresponding portions 3^a, 3^b, and 3^c.

The front, side and back walls, base and top when assembled are formed into a rigid structure in any suitable way as by spot welding, for example.

The closures or covers for the can racks are similar to those disclosed in my application afore-

said but differ from the same in that the closures 6 are formed of sheet metal and are provided with transverse strengthening ribs 6^a, and supporting hooks 9, and a single reinforcing bar 7 at the bottom.

The covers or closures 6 have locking dogs 8 which enter slots 1^a in the base to hold the lower end of a door against the wall portions 2^a, 3^a respectively. The covers also have hooks 9 near their upper ends which enter elongated slots 5 in the wall portions 2^a and hook over the wall portions at the lower ends of the slots 5. The top ends of the covers 6 are closed as at 6^b, the tops 6^b inclining downwardly outwardly from beneath the top 37 to drain rain water.

At both top and bottom the covers are provided with rubber bumpers 10 approximately U-shape in plan view, the bumpers having heels 10^a to fit over the folded back edges 6^c, see Fig. 6. To put a cover in place one sets the dogs 8 into the slots 1^a and lifts the cover until hooks 9 pass into slots 5. The cover is then let down until it is supported by the hooks in a position to be locked as will later fully appear.

The can passing opening 11 and the tool passing opening 12 are closable by a single door 13 hinged at 14 and provided with a releasable spring latch 15 of known construction. The door 13 also has a knob 16 on its front, while latch 15 is mounted on the back face of the door 13. On the back of the door and in line with opening 12 are locking bar element receiving straps 17 between which and the door a foot 35^a of locking levers 35 may enter.

Below opening 12 is a can collecting receptacle passing opening 18 which is closable by a door 19 whose upper end is deeply channelled as at 20 (Fig. 5) and whose lower end is provided with a shallow channel 21. A handle 22 is provided on the front or outer face of the door 19 and a locking bar guide 23 is secured to the back or inner face of the door.

A wall portion 2^a has a slot 36 in line with the guide 23 to permit passing a locking bar 24 into the guide 23 with its ends extended beyond the sides of the door (Figs. 2 and 5.) The bar 24 has an end piece 25 that lies at right angles to the plane of the bar and acts as a stop.

The locking mechanism for the two side covers 6 and the door 13 include a locking knob 26 turnably mounted on the front wall 2 by a mounting base 27 held in place by a washer 28 and nut 29. The locking knob 26 has a squared shank 30 on which fits the cam disc 31, a squared opening 32^c being provided for the purpose. The disc 31

has two eccentric slots 32, of which the ends 32^a and 32^b, however, are concentric with the disc and with one another.

Locking levers 35 are pivoted on lugs 34 secured to the back of the front wall 2, and are provided with cross bars at their ends. Each cross bar includes a locking portion 35^a and a portion 35^b. The portion 35^b at the upper end of the locking bar carried a stud 35^c which rides in a slot 32 in the cam 31 as best indicated in Figs. 2 and 4.

When lock 26 is unlocked by the usual key and turned counterclockwise levers 35 will be moved to withdraw upper portion 35^a from engagement with the tops of latch hooks 9 and will withdraw lower portions 35^b from engagement with the door straps 17 to release the covers 6 and door 13. To lock the covers 6 and door 13 closed knob 26 is turned in a clockwise direction to force the upper ends of lever 35 into holding engagement with hooks 9 and into loops 23. Relocking knob 26 by the key will in turn lock covers 6 and door 13 as will be clear to those skilled in the art.

It will be seen by reference to Figs. 2 and 4 that the axes of the studs 35^c lie in a horizontal plane that is located above the axis of the cam disc 31 so that when the cam disc is in the fully locked position the studs 35^c will lie in the concentric ends 32^b of the slots 32.

33 indicates cotter pins used to hold parts in place. 38 indicates the can chute, 39 a can retarding spring, 40 a can deflector, 41 an oil drip receiver, 42 a tool shelf and 43 a can collecting receptacle, all of which parts 38 to 43 inclusive are of known construction and are not claimed herein but see my patents aforesaid.

From the foregoing description, taken in connection with the accompanying drawings, it is thought that the construction, operation and advantages of the invention will readily appear to those skilled in the art.

What I claim is:

1. In apparatus of the class described, a chambered body having a wall that is provided with a set of stacked-can-receiving recesses and having a second wall that is provided with a can-receiving opening, a door for closing said opening, said door having a lock bar receiving strap, a cover for said set of stacked-can-receiving recesses, said cover having wall engaging elements, a lock bar pivoted to said second wall and having a rigid locking foot at each end, one of said feet being designed for entering said lock bar strap and the other foot being designed to engage one of said cover's wall engaging elements to secure said door and said cover in place, means connected to said lock bar for moving it to and from

its securing position, said means including a locking knob.

2. In apparatus of the class described, a chambered body having side walls that are each provided with a set of stacked-can-receiving recesses and having a second wall that is provided with a can-receiving opening, a door for closing said opening, covers for covering said recesses, locking bars pivoted to said second wall, said locking bars having rigid means to cooperatively engage said door and said covers to hold them in place, and a cam-carrying locking knob mounted on said second wall and being operatively connected to said locking bars.

3. In apparatus of the class described, a chambered body having side walls that are each provided with a set of stacked-can-receiving recesses and having a second wall that is provided with a can-receiving opening, a door for closing said opening, covers for covering said recesses, locking bars pivoted to said second wall, said locking bars having rigid means to cooperatively engage said door and said covers to hold them in place, and a cam-carrying locking knob mounted on said second wall and being operatively connected to said locking bars, the cam of said cam-carrying locking knob having eccentric slots with concentric ends and said locking bars having studs engaging in said slots.

4. In apparatus of the class described, a chambered body having side walls each provided with a set of can stacking recesses, and a cover for each set, said covers being of approximately U-shape in cross section and having locking dogs at their bottom ends, said chambered body having openings to receive said dogs, locking hooks secured to the sides of said cover at a suitable location above said dogs, said chambered body having slots to receive said hooks, and hold said cover in place, and means cooperating with said hooks for locking said cover in place, said means including locking bars pivoted to said chambered body and having rigid feet to engage said hooks, and means to rock said locking bar on its pivot from one position to another.

HARVEY J. SMITH.
